UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed February 16, 1924. Serial No. 693,166.

To all whom it may concern:

Be it known that I, JESSE A. B. SMITH, a citizen of the United States, residing in Stamford, in the county of Fairfield and State of Connecticut, have invented certain new and useful Improvements in Type-writing Machines, of which the following is a specification.

This invention relates to machines for cutting address stencils, and particularly to machines of the class wherein the stencil is fed past the printing point, without substantial bending, by means of a stencil-carrying frame arranged to be raised step by step to line-space the stencil, such, for example, as the machine disclosed in the patent to Elliott, No. 1,378,771, granted May 17, 1921.

In the machine of said patent, provision was made of a stencil-carrying frame pivoted on the carriage, far to the rear of the printing point, and provided, at its forward end, with clamping jaws to grip the stencils by their upper margins. The carrying frame was lifted, step by step, to line-space the stencils, by means of a thumb-wheel on a cam-shaft carried by the stencil-carrying frame. Rotation of the cam-shaft by the thumb-wheel caused the shaft to be raised bodily to lift the stencil-carrying frame. Provision was made of a detent-ratchet having teeth to determine successive line-space positions of the stencil-carrying frame, and to detain it in such positions. This ratchet was angularly adjustable with reference to the cam-shaft, and was provided with several sets of teeth which could be made effective selectively, each set of teeth being arranged to divide the rise of the frame, effected by the cam, into a different number of steps, and thereby to provide a different number of lines of writing within the limited space provided on a stencil.

It is an object of the present invention to utilize the above-mentioned features while making provision for a more rapid line-spacing of the work and returning of the carriage than was possible in the Elliott machine. To this end, provision is made of a line-spacing lever for the stencil-carrying frame arranged like the usual line-space lever of the Underwood machine to return the carriage at each line-spacing operation. This lever drives rearwardly a slide having a pawl pivoted on it at its rear end, which pawl extends forward to engage and drive

a line-space ratchet-wheel fast to the detent-ratchet. The line-space ratchet-wheel has sets of teeth corresponding in spacing and angular arrangement to the teeth of the detent-ratchet, and may be angularly adjusted with the detent-ratchet relatively to the frame-lifting cam-shaft to select the length of the line-feeding steps required. The cam-shaft, as it rotates, rises bodily step by step to lift the frame, and in this way line-feeds the stencil held by the frame. The line-space ratchet-wheel rises with the cam-shaft, and the line-space pawl, urged by a spring, rises with the ratchet-wheel, said pawl being pivoted on the line-space slide far to the rear of the ratchet-wheel, so that its rise will not materially affect its relation to the ratchet-wheel.

When a stencil has been completed, the stencil-frame may be swung upwardly and a stencil-releasing handle may be pressed to open the jaws, to permit the removal of the finished stencil and the insertion of a new one. In the present machine, as in the patent to Elliott referred to above, the operation of the jaw-opening handle is also effective to release the detent-ratchet to permit the return of the cam-shaft to its initial position under the influence of a return spring, so that the fresh stencil may be lowered to first writing-line position.

It is also important, in the present invention, that the line-space ratchet be disengaged from the line-space pawl at this time, since otherwise the line-space pawl and ratchet would prevent the return of the cam-shaft. In order to permit disengagement of the line-space ratchet from the line-space pawl, and to maintain the line-space pawl in position to intercept the ratchet and operatively engage it when it is again lowered, provision is made of a stop on the slide to limit the rise of the pawl about its pivot.

In the Elliott patent, provision was made of a strip-carbon device for making impressions on the backs of the stencils, this carbon being arranged to be line-fed by the platen of the machine, and hence being line-fed each time that the carriage was returned by the platen line-spacing handle. It is unnecessary, however, to line-space the carbon-strip at the conclusion of every line.

In the machine of the present invention, provision is made of take-off feed-rolls for the carbon, arranged to be rotated by a

finger-wheel, at the will of the operator, say once for every eight or ten line-spaces. The platen is not driven by the carriage-return line-space lever, but may be rotated by 5 means of a hand-wheel from time to time to expose different parts of the platen to the wear of the types.

In accordance with a further feature of the invention, provision is made of a guide-plate 10 which may be mounted on the type-segment of the machine to extend up in front of the platen, to assist in guiding the stencil down past the printing point during its insertion into the machine. To prevent 15 catching of the stencil on the type-bar guide of the machine, guide-fingers may be provided to extend upwardly and forwardly from the guide-plate alongside of the type-bar guide.

20 Other features and advantages will hereinafter appear.

In the accompanying drawings,

Figure 1 is a fragmentary sectional front elevation of a typewriting machine of the 25 Underwood type, having the present improvements applied thereto.

Figure 2 is a fragmentary plan view, showing the line-space lever and the line-space slide.

30 Figure 3 is a horizontal section through the cam-shaft and the ratchet-wheels.

Figure 4 is a vertical sectional view on the line 4-4 of Figure 1, showing in full lines the line-space ratchet-wheel lifted out 35 of engagement with the line-space pawl and in dotted lines another position of said ratchet-wheel. The ratchet-wheel is adjusted to provide three writing positions.

Figure 5 is a view similar to Figure 4, 40 showing the line-space ratchet-wheel set to provide four writing positions, and with the parts in actuated position at the end of the first feeding stroke. The first and fourth writing positions are illustrated in dot-and-dash lines.

Figure 6 is a view similar to Figure 4, 45 showing the line-space ratchet-wheel set to provide three writing positions, and with the parts in the first writing position. Other positions are illustrated in dot-and-dash lines.

Figure 7 is a view similar to Figure 4, 50 showing the line-space ratchet-wheel set to provide five different writing positions, and illustrating the carbon-strip mechanism. Other positions are indicated in dot-and-dash lines.

Figure 8 is a fragmentary plan view of the machine embodying the present invention.

Figure 9 is a vertical section on the line 9-9 of Figure 1, showing the stencil-gripping means, and the frame-lifting means immediately associated therewith.

65 The machine comprises types (not shown)

mounted in a type-bar segment 10 to swing upwardly and rearwardly through the throat of a type-guide 11 to print against the front face of a cylindrical platen 12 journaled by its axle 13 in the ends of a platen-frame 14. 70 The platen-frame is mounted on a carriage 15 for travel therewith in letter-feed and reverse directions. A stencil-carrying frame 16 comprising side members 17 is pivotally mounted upon a transverse rod 18 carried 75 by the platen-frame 14 far to the rear of the printing point of the machine. This stencil-carrying frame 16, at its forward extremity, is provided with fixed jaws 19 and co-operating pivoted jaws 20 to clamp the upper margin of an inserted stencil-card 21 to carry it past the printing point.

A cam-shaft 22 rotatable by a thumb-wheel 23 is journaled in the stencil-carrying frame 16, and has fast upon it a cam 24 to 80 engage a fixed abutment 24^a carried by a transverse rod 24^b mounted on the platen-frame 14. This cam 24 is so formed that the turning of the thumb-wheel 23 causes the cam-shaft 22 to be raised bodily, and as a consequence to swing the stencil-carrying frame 16 about the rod 18 to lift the stencil-card 21 in the machine relatively to the printing point. A detent ratchet-wheel 25 comprising sets of teeth 26, 27 and 28 is arranged to be made fast to the cam-shaft 22 in any one of three adjusted positions by means of recesses 29 in the ratchet-wheel 25 and a pin 30 (see Figure 3) on the cam 24. A finger-wheel 31 fast to the detent ratchet-wheel 25 is provided whereby the detent ratchet-wheel 25 may be moved longitudinally of the cam-shaft 22 against the pressure of a spring 32 to disconnect it from said shaft 22 for angular adjustment with 105 reference thereto. A detent-pawl 33 pivoted on the stencil-carrying frame 16 engages the teeth of the detent ratchet-wheel 25 to determine line-space positions of the stencil 21. There are three notches in that 110 portion of the ratchet-wheel occupied by the teeth 26, so that three line-space positions will be obtainable with this portion of the detent ratchet-wheel 25 effective while there are four more closely spaced notches in that 115 portion of the ratchet-wheel occupied by the teeth 27 to provide four line-space positions when the portion of the ratchet occupied by these teeth is effective, and similarly there are five notches in that portion of the 120 ratchet-wheel occupied by the teeth 28 to provide five line-space positions when this portion of the ratchet-wheel is effective.

Provision is made of a stencil-releasing handle 34 for moving the swinging jaws 15 away from the stationary jaws 19 when a stencil 21 has been completed. This handle 34 operates an arm 35 which is connected, through a link 35^a, to the detent-pawl 33 in such a manner that the detent-pawl is swung 125

out of engagement with the detent-ratchet wheel 25 concomitantly with the release of the stencil-card 21. A return spring 36 connected to the cam-shaft 22 and to the 5 stencil-carrying frame 16 restores the cam-shaft to its initial position, when permitted to do so, by the release of the detent-pawl 33. The mechanism thus far described is like that disclosed in the patent to Elliott, 10 referred to.

In accordance with the present invention, provision is made of a lever 37 arranged to line-space the stencil-carrying frame 16 and to return the carriage 15 at a single operation. This lever 37 is pivoted on the carriage 15, and has a toe 38 to engage and drive rearwardly a line-space slide 39 which is slidably mounted on the platen-frame and is bifurcated to slidably embrace the 20 transverse rod 24^b. A return spring 40 normally holds the line-space slide 39 at the forward limit of its movement. The line-space slide 39 has pivoted at its rear end a pawl 41 that extends forward to engage a line-space ratchet-wheel 42 fast on a shaft 43 which forms an extension of the detent-ratchet-wheel 25, and which is borne in an arm 44 of the stencil-carrying frame 16. The line-space pawl 41 is urged upward toward the line-space ratchet-wheel 42 by a leaf-spring 45 mounted on the line-space slide 39, and is limited in its upward movement by a shelf or stop 46 projecting above it from the line-space slide.

35 The line-space ratchet-wheel 42 has three sets of teeth 47, 48 and 49 which are spaced, respectively, to provide two, three and four feeding movements of the cam-shaft 22. The teeth 47 are spaced to correspond to the spacing of the teeth 26 on the detent-ratchet; the teeth 48 are spaced to correspond to the spacing of the teeth 27 on the detent-ratchet; and the teeth 49 are spaced to correspond to the spacing of the teeth 28 on the detent-ratchet. The line-space ratchet 42, being fast to the detent-ratchet 25, may be adjusted in unison therewith.

When the line-space and detent ratchets are set for two line-feeding movements, that 50 is, to write an address consisting of three lines, as shown in Figures 4 and 6, the line-space pawl 41 and line-space ratchet 42 will initially occupy the position shown in full lines in Figure 6. When the first line has 55 been written the lever 37 will be actuated to return the carriage and to operate the line-spacing mechanism to the dot-and-dash position indicated at 39^a, 41^a, 42^a in Figure 4, which position is the same as the first 60 dot-and-dash position of Figure 6. When the lever is released the pawl will travel from the first dot-and-dash position indicated in Figure 6 to engage behind the second one of the teeth 47. When the second 65 line has been written the lever will be again

actuated and released, whereupon the pawl will be reciprocated to lift the line-space ratchet to the position indicated at 42^b in Figure 6, the pawl itself returning to the position indicated at 41^b.

When the third line has been written it will be desired to remove the stencil from the machine. This may be done by seizing the stencil-release handle 34 and a co-operating abutment handle 50, and pressing 70 them together to move the movable jaws 20 to release the stencil-card. (See the dot-and-dash position of Figure 9.) These handles 34 and 50 at the same time may be lifted to swing the stencil-carrying frame 16 up to raise the line-space ratchet 42 clear of the line-space pawl 41, as shown in full lines in Figure 4. The disengagement of the line-space ratchet 42 from the line-space pawl 41 at this time is important because 75 these elements would prevent the return of the cam-shaft 22 to its initial position if they were permitted to remain engaged. As has been previously stated, the detent-ratchet 25 is released from the holding action 80 of the detent-pawl 33 by the pressure on the stencil-releasing handle 34, so that the cam-shaft 22 is free to be returned to its initial position by its return spring 36, which position is determined by engagement of a surface 51 on the cam 24 with a pin 52 on the 85 stencil-carrying frame.

When it is desired to write an address which consists of four lines the finger-wheel 31 is pulled toward the left against the pressure of the spring 32 to disconnect the detent-ratchet 25 and the line-space ratchet 42 from the cam-shaft 22. The shaft 43, on which both of said ratchets 25 and 42 are fast, is then rotated to bring the teeth 27 of the detent-ratchet into co-operative relation to the detent-pawl 33, and to bring the teeth 48 of the line-space ratchet 42 into co-operative relation to the line-space pawl 41. This relationship of the line-space ratchet 42 and pawl 41 is shown in Figure 5, in which figure the initial writing position of the line-space pawl and line-space ratchet are illustrated in dot-and-dash lines at 41^c and 42^c; the actuated position at the conclusion of the first line is illustrated in full lines; and the final writing position of the pawl and ratchet is illustrated in dot-and-dash lines at 41^d and 42^d.

In a similar manner the ratchets 25 and 42 may be adjusted relatively to the cam-shaft 22 to bring the teeth 28 on the detent-ratchet and the teeth 49 on the line-space ratchet to effective position when it is desired to write an address of five lines. In Figure 7 the initial writing positions of the line-space pawl and ratchet are illustrated in dot-and-dash lines at 41^e and 42^e, respectively; the actuated position at the conclusion of the first line is illustrated in full 115 120 125 130 lines at 41^f and 42^f.

lines; and the line-space positions of the pawl and ratchet are illustrated in dot-and-dash lines at 41^r and 42^r, respectively, in the fourth writing line position.

- 5 A carbon-strip 53 is fed forward from a holder 54 mounted on the rod 18, over a guide 55, down around the platen and thence up between feed-rolls 56 and 57 carried by a frame 58 mounted on the rod 18. A carbon-feeding finger-wheel 59 is fast to the roll 56, and may be rotated from time to time to feed the carbon 53 as it becomes worn. A detent-spring 60 co-operates with equally spaced notches 61 on the finger-wheel 59 to control the extent of carbon-feeding movement, and to detain the finger-wheel against accidental turning.

The carriage-returning lever 37 is not connected to the platen in the present machine, so that the platen is not ordinarily rotated. Hand-wheels 62, of which one is shown, are connected to the platen at its ends, and may be turned from time to time to bring a fresh surface of the platen 12 into position to receive the impact of the types.

When a finished stencil 21 has been removed from the stencil-holding jaws 19 and 20 and a fresh stencil has been gripped by them, the stencil-carrying frame will be ready to be lowered to locate the fresh stencil in its first writing line position. For the purpose of assisting in guiding the stencil to this position, provision may be made of a deflector-plate 63 mounted by fingers 64 upon the type-segment 10. This deflector-plate is inclined forwardly toward its upper end and has a rolled upper end to provide a wide, smooth reception opening for the stencils, and to keep them pressed back close to the platen at the line of writing. Forwardly-curved fingers 65 project upwardly from the deflector-plate 63 at opposite sides of the type-guide 11 to guide the stencil clear of said type-guide. The deflector-plate 63 engages the lower edge of the stencil and presses it slightly to the rear, thus assuring that the stencil will be held against the platen at the line of writing.

Variations may be resorted to within the scope of the invention, and portions of the improvements may be used without others.

Having thus described my invention, I claim:

1. In a machine for impressing characters on stencils, the combination with a platen, a carriage and a set of types, of stencil-holding means borne by the carriage and vertically movable adjacent the platen, a line-space lever, a line-space ratchet arranged for operation by the line-space lever having sets of teeth differently spaced to provide different numbers of writing lines on the stencil, a detent-ratchet having sets of teeth corresponding to the sets of teeth on the line-space ratchet, said detent-ratchet fast to the

line-space ratchet, the two ratchets being adjustable in unison to bring the different sets of teeth into use, and operating connections between the detent-ratchet and the stencil-holding means, including a cam moving with said ratchets step by step to lift the stencil-holding means, the extent of movement of the cam being controlled by the spacing of the effective teeth on the ratchets.

2. In a machine for impressing characters on stencils, the combination with a platen, a carriage and a set of types, of stencil-holding means borne by the carriage and vertically movable adjacent the platen, and means for raising the stencil-holding means, comprising a shaft on the stencil-holding means, a feed ratchet on the shaft, said shaft and ratchet arranged to rise with the stencil-holding means, feed-ratchet-operating means comprising a pawl mounted independently of the stencil-holding means, and means to cause the pawl to rise with the feed-ratchet to maintain co-operative engagement therewith.

3. In a machine for impressing characters on stencils, the combination with a platen, a carriage and a set of types, of stencil-holding means borne by the carriage and vertically movable adjacent the platen, means for raising the stencil-holding means, comprising a shaft on the stencil-holding means, a feed ratchet on the shaft, said shaft and ratchet arranged to rise with the stencil-holding means, feed-ratchet-operating means comprising a pawl mounted independently of the stencil-holding means, and means to cause the pawl to rise with the feed ratchet to maintain co-operative engagement therewith, and means to limit the rise of the pawl, the arrangement being such that the stencil-holding means may be lifted to free the feed ratchet from the pawl to permit the return of the ratchet to its initial position.

4. In a machine for impressing characters on stencils, the combination with a platen, a carriage and a set of types, of stencil-holding means borne by the carriage and vertically movable adjacent the platen, means for raising the stencil-holding means, comprising a shaft on the stencil-holding means, a feed ratchet on the shaft, said shaft and ratchet arranged to rise with the stencil-holding means, feed-ratchet-operating means comprising a pawl mounted independently of the stencil-holding means, and means to cause the pawl to rise with the feed ratchet to maintain co-operative engagement therewith, means to limit the rise of the pawl, the arrangement being such that the stencil-holding means may be lifted to disengage the feed ratchet and pawl to permit the return of the ratchet to its initial position, and means for restoring the feed ratchet to its initial position when the feed ratchet and pawl are disengaged.

5. In a machine for impressing characters on stencils, the combination with a platen, a carriage and a set of types, of stencil-holding means borne by the carriage and vertically movable adjacent the platen, means for raising the stencil-holding means, comprising a shaft on the stencil-holding means, a feed ratchet on the shaft, said shaft and ratchet arranged to rise with the stencil-holding means, feed-ratchet-operating means comprising a pawl mounted independently of the stencil-holding means, and means to cause the pawl to rise with the feed ratchet to maintain co-operative engagement therewith, means to limit the rise of the pawl, the arrangement being such that the stencil-holding means may be lifted to free the feed ratchet from the pawl to permit the return of the ratchet to its initial position, and means for operating the stencil-holding means to release a completed stencil and for concomitantly restoring the feed ratchet to its initial position when the feed pawl and ratchet are disengaged.

25 6. In a machine for impressing characters on stencils, the combination with a platen, a set of types, and means for presenting a stencil to the printing line of the platen, of carbon-controlling mechanism comprising means operable at will for feeding a carbon-strip around the platen to bring a fresh carbon-surface to the line of writing while said platen remains stationary.

35 7. In a machine of the kind described, a platen, a carriage, a set of types, a carbon-supply device at the introductory side of the platen, and carbon-feeding means at the delivery side of the platen, comprising a pair of co-operative feed-rolls and means 40 to control the length of the carbon-feeding steps effected by said feed-rolls.

8. In a machine of the kind described, a platen, a carriage, a set of types, a carbon-supply device at the introductory side of the platen, and carbon-feeding means at the delivery side of the platen, comprising a pair of co-operative feed-rolls, a finger-wheel for operating said feed-rolls independently of the platen, and detent-means constructed to 50 cause the feeding steps imparted by the feed-rolls to be of uniform length.

55 9. In a machine for impressing characters on stencils, the combination with a platen and a type-guide, of a deflector plate at the front of the platen having the upper edge thereof rolled over to provide a smooth reception opening between said edge and the platen, said deflector plate including guard fingers extending upwardly and outwardly 60 from said edge, at opposite sides of the type-guide, for guiding the lower edge of the card away from the type-guide to position within said reception opening.

65 10. In a machine for impressing characters on stencils, the combination with a plat-

en and a type-guide, of a deflector plate disposed adjacent the front of the platen for guiding a stencil-card down to the typing line, the upper and lower edges of said plate being bowed away from the platen whereby 70 to prevent fouling of the stencil-card thereon, during insertion in the machine or removal therefrom.

11. In a front-strike typewriting machine, the combination with a platen and a carriage therefor, of a frame overlying the platen and pivoted at its rear upon the carriage and overhanging the front of the platen, and at its front end having means for supporting a stencil-card pendent therefrom in front of the platen, a cam mechanism acting upon said frame and camming the same to different heights, a handle upon said carriage for returning the same, and operative means extending from said handle to said cam mechanism to cause the latter to elevate the frame step by step at successive reciprocations of the handle.

12. In a front-strike typewriting machine, the combination with a platen and a carriage therefor, of a frame overlying the platen and pivoted at its rear upon the carriage and at its front overhanging the platen, and at its front end having means for supporting a pendent stencil-card in front of the platen, a reciprocatory handle upon said carriage for returning the same, self-elevating means including a rotary cam carried by the free end of the frame, and means extending from the handle to said cam to 100 rotate the latter and thereby to elevate the frame step by step at successive reciprocations of the handle.

13. In a front-strike typewriting machine, the combination with a platen and a carriage therefor, of a frame overlying the platen and pivoted at its rear upon the carriage and overhanging the front of the platen, and at its front end having means for supporting a stencil-card pendent therefrom in front of the platen, a cam mechanism acting upon said frame and camming the same to different heights, a handle upon said carriage for returning the same, and operative means extending from said handle to said cam mechanism to cause the latter to elevate the frame step by step at successive reciprocations of the handle, said frame being movable down to initial position independently of said handle.

14. In a front-strike typewriting machine, the combination with a platen and a carriage therefor, of a frame pivoted at its rear upon the rear of the carriage and extending forwardly over the platen, a rotatable device including coating members mounted upon said carriage and said frame and effective when rotated to elevate said frame, a pawl-and-ratchet mechanism for operating said rotatable device, a carriage-returning han-

- dle, means to enable said carriage-returning handle to operate said pawl-and-ratchet mechanism to elevate said frame step by step at successive operations of said handle, 5 and a stencil-card holding means mounted independently of said pawl-and-ratchet mechanism and depending from said frame at the front of the platen.
15. In a front-strike typewriting machine, 10 the combination with a platen and a carriage therefor, of a frame pivoted at its rear upon the rear of the carriage and extending forwardly over the platen, a rotatable device including coacting members 15 mounted upon said carriage and said frame and effective when rotated to elevate said frame, a pawl-and-ratchet mechanism for operating said rotatable device, a carriage-returning handle, means to enable said carriage-returning handle to operate said pawl-and-ratchet mechanism to elevate said frame step by step at successive operations of said handle, and a stencil-card holding means 20 mounted independently of said pawl-and-ratchet mechanism and depending from said frame at the front of the platen, said rotatable device being returnable to normal position, together with said frame, independently of said pawl-and-ratchet mechanism. 25
16. In a front-strike typewriting machine, 30 the combination with a platen and a carriage therefor, of a frame pivoted at its rear upon the rear of the carriage and extending forwardly over the platen, a rotatable device including coacting members mounted upon said carriage and said frame and effective when rotated to elevate said frame, a pawl-and-ratchet mechanism for operating 35 said rotatable device, a carriage-returning handle, means to enable said carriage-returning handle to operate said pawl-and-ratchet mechanism to elevate said frame step by step at successive operations of said 40 handle, and a stencil-card holding means mounted independently of said pawl-and-ratchet mechanism and depending from said frame at the front of the platen, said rotatable device being in the form of a cam, said 45 pawl-and-ratchet mechanism including a ratchet-wheel connected to said cam and having differently spaced sets of teeth, and also including a drive pawl capable of operating seriatim all of the teeth in each set, settable means for determining which set of teeth shall be operated by the pawl, and releasable means for detaining said cam at any point to which it is rotated by said 50 pawl.
17. In a front-strike typewriting machine, 55 the combination with a platen and a carriage therefor, of a frame pivoted at its rear upon the rear of the carriage and extending forwardly over the platen, a rotatable de- 60 vice including coacting members mounted 65 upon said carriage and said frame and effective when rotated to elevate said frame and including a cam, a pawl-and-ratchet mechanism for operating said rotatable device and including sets of teeth, the teeth in each 70 set spaced differently from the others, means settable to enable said pawl to operate the teeth in any set, a carriage-returning handle, means to enable said carriage-returning handle to operate said pawl-and-ratchet 75 mechanism to elevate said frame step by step at successive operations of said handle, and a stencil-card holding means depending from said frame at the front of the platen.
18. In a front-strike typewriting machine, 80 the combination with a platen and a carriage therefor, of a frame overhanging the platen and pivoted at its rear, a reciprocating handle upon said carriage for returning the same, means extending from said 85 handle to said frame to elevate the frame step by step at successive reciprocations of said handle, said elevating means including a drive pawl connected to said handle, a ratchet, an elevating cam connected to said 90 ratchet, and a member adjustable independently of said handle and pawl for regulating the extent of line-spacing movements of the stencil-card, and a stencil-card holding means mounted independently of said pawl, 95 ratchet and cam and pendent from said frame in front of the platen.
19. In a front-strike typewriting machine, 100 the combination with a platen and a carriage therefor, of a frame overhanging the platen and pivoted at its rear, a reciprocating handle upon said carriage for returning the same, means extending from said handle to said frame to elevate the frame step by 105 step at successive return movements of the carriage effected by said handle, said elevating means including a train mounted partly upon the carriage and partly upon said pivoted frame, and said train including a pawl-and-ratchet mechanism and a frame- 110 elevating cam operable thereby, and a stencil-card holding means mounted independently of said pawl, ratchet and cam and pendent from said frame in front of the 115 platen.
20. In a front-strike typewriting machine, 120 the combination with a platen and a carriage therefor, of a frame overhanging the platen and pivoted at its rear, a reciprocating handle upon said carriage for returning the same, means extending from said handle to said frame to elevate the frame step by step at successive return movements of the carriage effected by said handle, said elevating means including a train mounted partly upon the carriage and partly upon said pivoted frame, said train including a pawl-and-ratchet mechanism and a frame- 125

elevating cam operable thereby, a rotatably adjustable ratchet-wheel being included for regulating the extent of the line-spacing movements imparted to the stencil-card through said train, said ratchet-wheel having groups of teeth thereon, the spacing in each group different from the other groups, and the pawl and handle being co-operative with the teeth in any group, and a stencil-card holding means mounted independently 10 of said pawl, ratchet and cam and pendent from said frame in front of the platen.
